Siegmund Werner, South Orange, N.J., assignor to Siegmund Werner, Inc., Bloomfield, N.J., a corporation of New Jersey

Filed Sept. 19, 1960, Ser. No. 62,189

Term of patent 3½ years

(Cl. D87—5)

Fig. 1.

Fig. 2.

Fig. 3.

Fig. 4.

FIG. 1 is a rear elevational view of a picnic bag embodying my novel design;

FIG. 2 is an end view of the bag illustrated in FIG. 1;
FIG. 3 is a top plan view; and

FIG. 4 is a perspective view of the bag illustrating the front, top and one end thereof.

Conventional shading is employed on the body and associated diamond-shaped elements to indicate color contrast rather than any specific color.

I claim:

The ornamental design for a picnic bag, substantially as shown and described.
